UNITED STATES PATENT OFFICE.

JOHN G. G. EKLUNDH, OF COLUMBUS, OHIO, ASSIGNOR TO THE UNIVERSAL MILKING MACHINE COMPANY, A CORPORATION OF OHIO.

PULSATOR FOR MILKING MACHINES.

Application filed March 24, 1919. Serial No. 284,553.

To all whom it may concern:

Be it known that I, JOHN G. G. EKLUNDH, a subject of the King of Sweden, residing at Columbus, in the county of Franklin 5 and State of Ohio, have invented certain new and useful Improvements in Pulsators for Milking Machines, of which the following is a specification.

My invention relates to pulsator mechanism, of the type commonly employed in milking apparatus, and more particularly to valve operating means therefor. It is to be understood however that the mechanism is not limited to use in conjunction with 15 milking apparatus, and that the valve tumbler means may be applied to other mechanism than air operated pulsators.

The object of the invention is to simplify the structure as well as the means and mode 20 of operation of such valve tumbler mechanism, whereby it will not only be cheapened in construction, but will be more efficient in operation, positive in action, economical in manufacture, and unlikely to get out of 25 repair.

A further object of the invention is to provide valve operating mechanism under the control of a prime mover which will be inoperative until such prime mover has 30 reached a predetermined point in its path of travel.

With the above primary and other incidental objects in view as will more fully appear in the specification, the invention consists of the features of construction, the 35 parts and combinations thereof, and the mode of operation, or their equivalents, as hereinafter described and set forth in the claims.

40 Referring to the drawings, Fig. 1 is a perspective view of a pulsator embodying the present invention. Fig. 2 is a top plan view thereof. Fig. 3 is a top plan view showing the relation of the parts at the moment of reversal. Fig. 4 is a transverse sectional view. Fig. 5 is a top plan view of a modification. Figs. 6 and 7 are detail sectional views of the pulsator and control valve ports and valve connections. Fig. 8 45 is a detail view of a modification of the control valve and Fig. 9 is a further modification thereof.

Like parts are indicated by similar characters of reference throughout the several 50 views.

The form of pulsator illustrated in the drawings, comprises a cylinder 1 mounted upon a suitable base or standard 2, the top of the cylinder is extended to form a deck or table upon which is mounted the alternating valve mechanism hereafter described. Within the cylinder is a reciprocating piston 3 which constitutes the prime mover by which the valve tumbler mechanism is actuated. The piston 3 is actuated to and 55 fro by air pressure directed to one end or the other of the cylinder by the alternation of the control valve. The preponderance of air pressure necessary to the movement of the piston may be effected either 60 by exhaustion of air from one end of the cylinder and admission of air at atmospheric pressure to the opposite end of the cylinder, or it may be effected by admission of 65 air under increased pressure.

Air is supplied to and exhausted from the cylinder 1 through ducts 4 leading from the opposite ends of the cylinder to ports 5 located in the top or deck of the device. In the present instance these ports are located 70 within a groove or recess 6, the bottom of which forms the seat for a reciprocatory valve member 7. The ports 5 and related ducts 4 are alternately opened to atmosphere and connected with an exhaust port 75 8 located intermediate the ports 5 by the movement of the valve member 7. The exhaust port 8 communicates with a suction duct or passage 9 leading downward to a main exhaust passage hereafter referred to. 80 It will be understood that in the event the device is operated by compressed air such actuating medium would be supplied 85 through the passage 9 and port 8.

The top or deck 10 of the device is 90 bounded by a flange 11 which forms both a stop and a guide for the valve operating means. This flange may be integral but for convenience of manufacture may be formed separate and subsequently attached 95 to the deck or top 10 of the pulsator. The valve 7 reciprocating in its depressed seat in the deck 10 has been shown in the drawing projecting beneath the flange 11 at the limit of its stroke. The valve 7 is provided with a pocket or recess in its underside forming a communicating passage between the ports 5 and 8. The main valve member 7 may be provided with a loose-fitting recessed insert in which the communica- 100 105

cating recess or pocket is located as shown in Fig. 9. However such auxiliary floating valve member forms no part of the present invention.

5 Pivoted upon a fixed stud 12 located in the top of the pulsator is an operating lever 13. This lever is oscillated to and fro in unison with the movement of the piston 3 by means of a stud or pin 14 carried by 10 the piston, which pin extends through a slot 15 in the top of the cylinder and engages in a slot 16 in the operating lever 13. Pivoted to the free end of the operating lever 13 is a valve actuator 17 the head of 15 which is of lanceolate form and provided with a slot 18 in which engages a stud or pin 19 carried by the valve 7. The actuator 17 is free for oscillatory movement about its connection with the operating lever. It 20 will be noted however that the fulcrum 20 of the valve actuator is shifted to and fro with the movement of the prime mover or piston. The lanceolate head of the actuator is so shaped that as it rides upon the 25 flange 11 during the shifting movement of the fulcrum 20 the relation of the pin 19 with the flange 11 is unchanged and the valve remains at rest.

That is to say that the arcuate faces of 30 the lanceolate head of the actuator are developed with such relation to the center line of the actuator head that the actuator will shift longitudinally and simultaneously turn about the valve stud 19 while the fulcrum 20 is being shifted by the movement 35 of the operating lever, without moving the valve. This is due to the fact that the proportions of the head are such that the radial distances from the center of the pin 19 to 40 the margin of the head in its different positions of adjustment, measured in line with the movement of the valve 7, are substantially constant. The flange 11 thus serves for a guide for the head in its longitudinal 45 shifting movement.

An actuating spring 21 connects the head of the actuator 17 and the fixed stud 12. This spring for convenience is connected to a pin 22 carried by the actuator head.

50 The spring 21 by its retractive tendency holds the actuator head firmly against the marginal flange 11 and so maintains the valve in operated position until the piston approaches the limit of its stroke. As the 55 piston approaches the limit of its stroke the fulcrum 20 of the actuator is shifted beyond a dead center position in relation with the spring connections 12 and 22, whereupon the contraction of the spring immediately oscillates the actuator 17 into 60 engagement with the opposite flange 11, carrying with it the valve 7 to reverse position. The reversal of the valve of course effects the reversal of the piston and the cycle of operations is repeated. In Fig.

3 the operating lever 13 is shown at the limit of its movement and the fulcrum 20 beyond the dead center with the spring exerting its pull upon the actuator which is thereby turned to the dotted line position. The operating lever 13 and actuator 17 may be compared to a toggle link construction which is reversed to and fro against the tension of the spring 21 connecting the extremities of such toggle link 75 construction. The toggle is operated to a straightened position to place the spring under tension, and when the toggle is moved slightly beyond its straightened position the spring completes the movement of the 80 toggle.

The spring 21 not only serves to reverse the valve but it also holds the valve in its reversed position until the moment of the succeeding operation of the valve. 85

The suction duct 9 leading to the port 8 is a branch conduit communicating with a main vacuum conduit 23 extending beneath the cylinder 1 and thence upward to a port 24. The port 24 is alternately connected 90 with ports 25 at opposite sides thereof by the alternation of a pulsator valve 26 seated in a slot or recess 27 in the top or deck of the device. This valve is provided with a pocket or depression 28 in its under side, 95 which affords a communicating passage between the respective ports 24 and 25. The ports 25 communicate with hose or tubing connections 29 with which the teat cups or other intermittently operated elements are 100 connected. To operate the pulsator valve 26 the operating lever 13 has been extended beyond its pivotal connection 12, and is provided with a slot 30 in which engages a stud or pin 31 carried by the valve 26. The 105 valve 26 is thus shifted to and fro in unison with the movement of the piston.

The main vacuum conduit 23 is connected with a suitable suction device or with a supply of air under pressure according to 110 the elected method of operation. The reversal of the piston is controlled by the movement of the valve 7 which governs the supply of air to the cylinder 1. The movement of the piston is transmitted, not only 115 to the valve 7 but to the valve 26 by which the influence of the actuating media is exerted alternately upon the operated devices connected to the respective connections 29.

It will be obvious that without in any 120 way changing the construction or operation of the parts the spring 21 may be connected to the stud or pin 31 in lieu of the fixed stud 12. In such event the spring would be given a greater tensioning movement and its direction of pull upon the actuator would be changed in unison with the shifting of the fulcrum 20 thereby accentuating the influence of the spring upon the valve 7.

In Fig. 5 there is shown a modification 130

of the construction previously described, in which the actuator for the valve 7 is extended into an elongated lever 32 which is pivoted directly upon the stud or pin 14 carried by the piston. The fulcrum of this actuator lever 32 upon the pin 14 is shifted to and fro beyond a dead center in relation with the spring connections 12 and 22 to reverse the valve in the same manner before described.

If so desired the valve 7 may be omitted and the actuator, whether in the form 17 or 32, may be utilized as the control valve by providing a recess or pocket 33 in the under side of the actuator head as shown in Fig. 8. In such case the ports 5 and 8 would be located flush in the deck or top 10 instead of in the recess 6. To insure perfect contact of such valve element with its seat the head would preferably, though not necessarily, be provided with a loose insert 34 free for movement toward its seat independent of the actuator, this insert having therein the intercommunicating passage connecting the ports is held upon the seat by air pressure.

From the above description it will be apparent that there is thus produced a device of the character described, possessing the particular features of advantage before enumerated as desirable, but which obviously is susceptible of modification in its form, proportion, detail construction and arrangement of parts without departing from the principle involved, or sacrificing any of its advantages.

While the invention has been described in language more or less specific as to certain structural features, it is to be understood that the invention is not limited to the specific details shown and described, but that the means and construction herein disclosed comprise but one of several modes of putting the invention into effect, and the invention is therefore claimed in any of its forms or modifications within the legitimate and valid scope of the appended claims.

Having thus described my invention I claim:

1. In a mechanism of the character described, a movable valve member, an oscillatory actuator therefor, a spring adapted to oscillate the actuator, and means for simultaneously shifting the spring and the fulcrum of said actuator to and fro toward each other to cause the actuator fulcrum and the line of force of said spring to simultaneously approach and pass each other, whereby the actuator will be alternately oscillated in opposite directions to effect the reversal of said valve.

2. In a mechanism of the character described, the combination with a body having therein a plurality of ports to be alternately opened and closed, of a valve con-

trolling the opening and closing of said ports, an oscillatory control member therefor, an actuating spring connected to said member, and means for shifting the fulcrum of the oscillatory member, a midlength bearing upon which the member oscillates during such shifting movement to cause the line of force of said spring to approach these fulcrums, whereby the oscillatory member will be alternately actuated in opposite directions by said spring to alternately open and close said ports.

3. In a mechanism of the character described, an oscillatory member, an actuating spring therefor, and means controlled by the oscillation of said oscillatory member for shifting the fulcrum of said member to and fro across the line of force of said spring, a valve having operative connections with said oscillatory members, said spring being operatively connected with said oscillatory member at a point beyond the operative connection of said member with the valve, whereby said oscillatory member will be alternately oscillated in opposite directions under the influence of said spring.

4. In a mechanism of the character described, a movable member to be operated, a pivoted actuator having operative engagement therewith, a spring adapted to oscillate the actuator connected therewith eccentrically in relation with the point of operative engagement of the actuator and movable member, and means for shifting the fulcrum of the actuator to and fro across the line of force of said spring, whereby the actuator and movable member will be operated first in one direction and then in another direction, under the influence of the spring.

5. In a mechanism of the character described, a pair of pivotally interconnected lever arms forming a toggle-like link, a spring connecting the respective arms of said interconnected toggle-like link, a movable member to be operated connected with one of said lever arms, and means to oscillate the other arm to reverse said toggle-like link to and fro beyond a dead center to effect the alternation of the movable member under the influence of said spring.

6. In a mechanism of the character described, a movable member to be operated, an oscillatory operating lever having a fixed pivotal connection, an oscillatory actuator pivoted to the free end of the operating lever and operatively connected with said movable member, means for oscillating the operating lever, and a spring tensioned by the oscillation thereof adapted to oscillate the actuator independent of the movement of the operating lever to shift said movable member.

7. In a mechanism of the character described, an oscillatory lever having a fixed pivotal connection, a second oscillatory lever

5 pivoted to the free end of the first lever, means controlled by the oscillation of the second lever for effecting the oscillation of the first mentioned lever, and an actuating spring for the second mentioned lever tensioned by the oscillation of the first mentioned lever.

8. The combination with a fluid pressure operated prime mover of a movable control 10 valve governing the action of the fluid pressure upon said prime mover, an oscillatory actuating member for said valve the opposite ends of which are simultaneously moved in opposite directions to and fro in 15 unison with the movement of the prime mover, and a spring placed under tension by the movement of the actuating member adapted to oscillate the actuating member to shift the valve as said prime mover approaches the limit of its stroke in either 20 direction.

9. In a mechanism of the character described, an oscillatory control member having a movable fulcrum, means for shifting 25 said fulcrum to and fro, and a spring adapted to oscillate said control member as the movable fulcrum thereof approaches the limit of its to and fro movement, and means whereby the line of force of the spring is 30 automatically advanced to meet said fulcrum, by the shifting movement thereof, substantially as specified.

10. In a mechanism of the character described, an oscillatory control member an 35 oscillatory support therefor, fluid pressure operated means for oscillating said support and a spring adapted to oscillate the control member in a direction opposite to the direction of oscillation of said support under the 40 influence of the fluid pressure, and a valve member controlled thereby to govern the action of the fluid pressure upon said operating means, as the movable support approaches the limit of its to and fro movement. 45

11. The combination with fluid pressure operated mechanism of a movable valve member, two interengaged oscillatory levers, alternately positioned in reverse angular relation, and shifted to and fro by the 50 operation of the fluid pressure operated mechanism, an operative engagement between one of said levers, and said valve and a spring adapted to oscillate the valve engaging lever independent of the other lever to shift the valve as the fluid pressure operated mechanism approaches the limit of its stroke.

12. In a construction of the character described, a reciprocating member to be operated, a reciprocating prime mover, an oscillatory actuating member one end of which is operatively connected with, and moves in unison with the prime mover, the 60 other end of which moves simultaneously in

the opposite direction, and a spring placed under tension by the action of the actuating member adapted to bodily swing the actuating member about its operative connection with the prime mover to its alternate position to reciprocate the member to be operated as the prime mover approaches the limit of its stroke. 70

13. A movable control member, a prime mover governed by the movement of said 75 control member, an interconnecting actuating member, one end of which is connected to and moves in unison with the prime mover, the other end of which moves simultaneously in the opposite direction and a 80 spring adapted to oscillate the actuator independent of its oscillatory movement under the influence of the prime mover to shift said control member as the prime mover approaches the limit of its stroke. 85

14. In a mechanism of the character described, a valve member capable of alternating movement, a spring for imparting a snap over action to the valve, an oscillatory actuating lever having operative engagement with the valve and extending beyond its point of such engagement, a pivotal connection for the actuating lever at one side of its point of operative engagement with the valve, said pivotal connection being reciprocated to and fro by said fluid operated means, said spring being connected to the actuating lever at the opposite side of the point of operative engagement of the lever with the valve, whereby the shifting of the 100 pivotal connection will effect a movement of the point of connection of the spring in the opposite direction until the line of force of the spring and pivotal connection of the lever pass one beyond the other, whereupon 105 the spring will oscillate the lever about its pivotal connection to impart movement to the valve.

15. In a construction of the character described, a movable member to be operated, 110 an actuating lever having a sliding pivotal connection with said movable member, means for moving said lever to and fro a guide for said lever during its sliding pivotal movement whereby said movable 115 member will be unaffected thereby, and a spring adapted to shift the movable member when the lever has been oscillated about its connection therewith to a predetermined position. 120

16. In a mechanism of the character described, a valve member capable of alternating movement, a spring for imparting a snap over action to the valve, an oscillatory actuating member having an intermediate 125 operative connection with said valve, means for oscillating the ends of the actuating member simultaneously in opposite directions about its operative connection with the valve to tension said spring, whereupon the 130

actuating lever is oscillated in unison with the movement of the valve about a center eccentric with its initial oscillatory movement under the influence of the spring.

- 5 17. The combination with a fluid pressure operated mechanism, of an alternating control valve governing the action of the fluid under pressure upon the mechanism, of snap over tumbling means for the valve including
 10 an oscillatory lever movable in unison with the fluid pressure actuated mechanism, a second lever pivoted to the first lever and having its free end operatively connected with the valve, a spring connected to the second lever
 15 and tensioned by the movement of the first lever to actuate the second lever independent of the first lever by the reaction of the spring when the interpivotal point of said levers is moved across the line of force of the spring,
 20 to shift said control valve.

18. In a mechanism of the character described, a valve member capable of alternating movement, a spring for imparting a snap over action to the valve, an oscillatory actuating member having operative connection with the valve, and means for simultaneously shifting the spring and fulcrum of said oscillatory member toward and across each other, whereupon said spring will effect the movement of the valve and actuator to alternate positions.

19. In a mechanism of the character described, a valve member capable of alternating movement, a spring for imparting snap over action to the valve, an oscillatory actuating lever having operative engagement with the valve, stationary stop members engaged by the actuating lever at the opposite limits of its stroke, means for shifting the fulcrum of said actuating lever to and fro across the line of force of said spring whereby the spring will alternately influence the movement of the valve and actuator to alternate positions.

- 45 20. In a mechanism of the character described, a valve member capable of alternating movement, a spring for imparting snap over action to the valve, an oscillatory actuating lever having operative engagement with the valve, stationary stop members engaged by the actuating lever at the opposite limits of its stroke, upon which said oscillatory actuating lever has a rocking movement, means for shifting the fulcrum of the actuating lever to and fro to impart such rocking movement thereto in relation with the engaged stop, said spring effecting the reversal of the actuating lever into engagement with the opposite stationary stop upon
 50 the shifting of said fulcrum across its line of force.

21. In a mechanism of the character described, a valve member capable of alternating movement, a spring for imparting snap over action to the valve, an oscillatory

actuating lever having operative engagement with the valve, stationary stop members engaged by the actuating lever at the opposite limits of its stroke, one of the engaging members having a cam face formed thereon whereby said actuating lever is guided in its adjusting movement, means for shifting the fulcrum of said lever to adjust the actuating lever to position for reversal under the influence of said spring.

70 22. In a mechanism of the character described, a valve member capable of alternating movement, a spring for imparting snap over action to the valve, an oscillatory actuating lever having a sliding pivotal engagement with the valve, spaced guides engaged by the lever at the opposite limits of its stroke, cam faces on said lever contacting the guides to control the adjusting movement of the lever, and means to shift
 80 the pivotal connection of the lever in relation with the line of force of the spring to effect the alternation of the lever and valve under the influence of the spring.

85 23. In a mechanism of the character described, a valve member capable of alternating movement, two interpivoted oscillatory arms forming a toggle like link, a spring tending to flex the said toggle like link against the tension of which the interpivotal connection of said arms is reversible, a valve capable of alternating movement operatively connected with one of said oscillatory arms, and means for oscillating said arms to and fro across the line of dead center against the tension of said spring, whereupon the further flexing of the toggle like link is effected by oscillating one member independent of the other by the action of the spring to effect the reversal of the valve member.

90 24. In a snap over tumbler mechanism for valves, the combination with a fluid pressure operated prime mover, a movable control valve governing the action of the fluid pressure upon the prime mover, a pivoted actuating lever for the valve, an actuating spring for the lever, the pivotal connection of the lever being movable to and fro across the line of force of the spring in unison with the travel of the prime mover, said lever having a rocking bearing between the point of connection of the spring and the pivotal connection about which the lever oscillates under influence of the spring to effect a movement of the spring connection in a direction opposite the direction of movement of the pivot and in unison therewith.

110 25. In a snap over tumbler mechanism for valves, the combination with a fluid pressure operated prime mover, a movable control valve governing the action of the fluid pressure upon the prime mover, an actuator link for the valve pivotally connected at its opposite ends for oscillating movement

about either connection upon shifting movement of the other connection, said link being movable about one of its pivotal connections by shifting movement of its opposite connection under influence of the prime mover, a spring tensioned by such movement to subsequently oscillate the link about its shifted connection to shift the first men-

tioned pivotal connection in opposite direction and with it the valve. 10

In testimony whereof, I have hereunto set my hand this 15th day of March, A. D. 1919.

JOHN G. G. EKLUNDH.
